VANITY CASE CONSTRUCTION

Alfred F. Reilly, North Attleboro, Mass.

Application April 4, 1932, Serial No. 602,916

15. Claims. (Cl. 132—82)

The invention relates to vanity cases and, in respect to some of its more specific features, to powder dispensers.

One object of the invention is to provide an attractive vanity case. Another object of the invention is to provide a simplified construction for vanity cases. Another object of the invention is to provide a vanity case which shall occupy but a small space. Another object of the invention is to provide a dispenser for vanity cases which shall automatically fill the puff with the desired amount of powder. Other objects will be in part obvious or in part pointed out hereinafter.

15 In the accompanying drawings, in which are shown three of various possible embodiments of the mechanical features of this invention, and in which cross-sectional views are adopted as illustrative of the construction disclosed, it being understood that the vanity case may be circular in plan view,

Figure 1 is a cross-sectional view of a vanity case constructed in accordance with the invention;

25 Figure 2 is a cross-sectional view in a different plane of the vanity case of Figure 1, showing the hinges and the latch and a slightly modified form of the dispensing member;

Figure 3 is a plan view (on a smaller scale than Figures 1 and 2) showing a modified form of vanity case;

30 Figure 4 is a cross-sectional view taken on the line 4—4 of Figure 3, showing the parts on the same scale as in Figures 1 and 2;

35 Figure 5 is a cross-sectional view illustrating another form of the invention; and

Figure 6 is a view of the bottom part of vanity case of Figure 5, showing the sifter cap in place.

Similar reference characters refer to similar parts, throughout the several views of the drawings.

Referring first to Figure 1, I provide a piece of flexible impervious material 20, preferably leather. This material is preferably so shaped that it may be said to lie in or have a surface of the second order, by reason of which, although made of a single piece and having no seam, fold or pucker, it has the shape of a bag or pouch as shown. The expression "surface of the second order" is a mathematical one and denotes a surface which, for example, could not be made by any amount of folding of a piece of paper. It should be noted that while a cylindrical surface is a surface of the first order, a seamless cylinder cannot be made from a flat, membranous ma-

terial without change of condition involving a rearrangement of the fibers of that material, and thus the existence of a seamless cylindrical portion such as the portion 28a of the material 20 distinguishes it in kind from ordinary flat material which is cut and sewn, pucker, or similarly treated to force it to assume such a shape.

The material 20 likewise has an annular circumferential portion 28b whose surface, after the material is formed, is in a plane and thus is a surface of the first order, this portion 28b merging with and being seamlessly integral with the remainder of the material 20. Any desired method or process may be adopted to make the material 20 as described.

15 Still referring to Figure 1, I provide a ring 21 which is preferably of a single piece of metal and has extending around its entire circumference an upper and inwardly extending portion 22, and a lower inwardly extending portion 23 that likewise extends around the entire circumference of the ring 21. The portion 28b of the material 20 is held by ring 21, being located between the upper and lower portions 22 and 23 which, by means of a press or other suitable instrumentality, are set so as to grip the leather or other material constituting the portion 28b, either directly or by compressing an interposed member against it as will hereinafter more fully appear.

20 Referring now to Figure 2, a hinge element 26 is attached to or formed integral with the ring 21. Preferably, in order to avoid the use of solder or the like, this hinge element 26 is formed by pressing outwardly a portion of the circumference of the ring 21, and then cutting substantially triangular shaped pieces out of opposite sides of this portion which thus constitutes the hinge element and through which may be passed a hinge pin 27. A cover which is generally designated by the numeral 28 has a pair of hinge 30 elements 29, 29 (better shown in Figure 3 the hinge construction being the same in this modification as in the modification of Figures 1 and 2) which preferably are integral with the cover to avoid the use of solder, and by means of the parts 35 described the cover 28 is hinged to the ring 21.

25 Referring to Figures 1 and 2, the cover 28, in this particular embodiment of the invention, comprises a disc-like piece of sheet metal 30 having an outer peripheral portion 31 which, by engagement with the rounded upper part 22 of the ring 21, forms a seal to prevent the escape of loose powder from the vanity case. The portion 31 may be bounded on the inside by an annular indentation 32, as thereby the strength of the 30

cover 28 and its resistance to deformation is enhanced, and to the same end the central portion of the sheet metal is desirably slightly bulged as shown, these features also assisting in rendering the article attractive in appearance. The hinge elements 29, 29 may be made by striking downwardly a portion of the metal of the cover; in other words, when the cover is initially cut, projecting portions are left in the otherwise circular piece of metal.

Still referring to Figures 1 and 2, suitably secured to the sheet metal 30, as by soldering, is a metal ring 34 having an inwardly extending portion 35 which is spaced from the under side of the sheet metal member 30. In the space so defined fits a rouge holding member 36 comprising a cylindrical portion 37, an outwardly extending portion 38, and a U-shaped portion 40 in the form of an integral ring. The rouge holding member 36 may be affixed to ring 34 by means of an interposed securing and retaining ring 41 adapted to be readily fastened to the member 36 and to be quickly and irremovably secured to the ring 34 in a manner that will now be described.

The retaining ring 41 is preferably formed of a single piece of metal and, considered in cross-section at any point as shown in Figures 1 and 2, includes an arcuate lower portion 42 merging into a flat upper portion 43 from which extends vertically upwards a cylindrical portion 44, the latter being spaced from the outside edge of the portion 42 leaving a marginal peripheral part 42a of the portion 42 extending outwardly beyond the outside of the cylindrical portion 44. At a plurality of points in the circumference of the cylindrical portion, preferably three or more, are integral upward extensions 45. The U-shaped annular portion 40 of the rouge holding member 36 is of a size to fit inside the cylindrical portion 44 and to be supported by the portion 43 of the retaining ring 41, and is secured to the ring 41 by bending over the extensions 45, which thus constitute tabs to hold the member 36 firmly in place. In the outside of the cylindrical portion 44 are formed a plurality of snaps 46, which may be located in alignment with the tabs 45, and preferably are made by indenting the inner side of the cylindrical portion 44 with a tool which is so shaped that the snaps constitute segments of cones with their bases on the bottom. The outer diameter of the cylindrical portion 44 is less by a slight margin than the inner diameter of the opening defined by the ledge 35, and when the retaining ring is placed in this opening and forced with a certain degree of pressure into it, the snaps 46 give enough to allow it to go into place with the portion 42a against the portion 35, and when that is done the rouge holding member 36 is firmly attached to the cover 28. By means of the retaining ring 41 or a similar device any one of a number of different styles of rouge holding members, mirrors or the like may be fastened to the cover 28, as the ring 41 can be quickly and firmly secured to the ring, by means of the tabs 45, fairly wide tolerances being permissible owing to the fact that the parts 42 and 43 definitely limit downward movement of the particular device selected with respect to the ring, while the latter is formed to fit nicely within its holding ring 34, and when snapped into place is firmly and substantially irremovably secured.

Still referring to Figures 1 and 2, the cylindrical portion 37 and the inside of the cover 28 define a compartment 48 from the reception of rouge

49 adhering to a disc 50. Referring to Figure 1, a portion of the metal 38 is struck downwardly and rolled over to form one or more hinge members 51 by means of which a metal disc 52 having corresponding hinge members is hinged to the member 36 by a hinge pin 54. The disc 52 constitutes a cover for the compartment 48 and may be polished to present a mirrored surface. Struck downwardly from the portion 37 of the member 36 is a tab 55 adapted to receive and hold in position the mirror cover 52 which, however, may be opened by inserting a finger nail under a downwardly bent portion 56 constituting an opening device.

Referring again to Figure 2, extending from the periphery of the outer portion 31 of the cover 28 and preferably opposite the hinge elements 29 is a downwardly extending loop 57 which may be and preferably is integral with the sheet metal 30. This loop 57 constitutes a snap catch adapted to embrace the outer rounded edge of the ring 21 and to hold the cover 28 resiliently in position, causing the peripheral portion 31 to bear firmly against the upper part 22 of the ring 21. When it is desired to close the cover 28 the peripheral portion 31 and the ring 21 are pressed together with the fingers, and the cover snaps shut. Referring to Figures 2 and 3, for the convenient unfastening of the snap catch 57, I provide a U-shaped piece of wire 58 which is secured in any desired manner, as by soldering, to the ring 21, the front portion thereof being inclined upwardly from the plane of the ring 21. When the loop 57 and the wire 58 are grasped between two fingers and pressed together the cover 28 is opened.

Still referring to Figures 1 and 2, interposed between the upper portion 22 of the ring 21 and the circumferential portion 20b of the material 20 is a rim 60 of a bezeled member 61. The bezeled member 61 has a cylindrical portion 62 extending downwardly from the rim 60 and lying just inside the cylindrical portion 20a of the material 20. Extending inwardly from the bottom of the cylindrical portion 62 is an annular ledge 63.

The bezel 61 serves for the removable support of a dispensing member received within the pouch formed by the material 20 and separating that pouch into a compartment 64 for powder and a compartment 65 for filtered or dispensed powder and for a puff 66. Referring now to Figure 1, the filtering or dispensing member includes a metal rim 67 which may be similar in construction to the ring 21. Secured in place by the rim 67 is a pouch-like piece of pervious material 68. This pouch-like piece of pervious material may, if desired be of a single piece and formed into a surface of the second order or it may be pieced material and desirably is made of cloth having a loose weave, or some similar substance such as the wire cloth 60 from which strainers are made, so that it will be compressible or collapsible.

Considering now the use of the vanity case of Figure 1, the rim 67 and with it the entire dispensing and powder containing member 59 is removable from the bezel 61, being normally resiliently retained in the position shown in Figure 1 by means of indentations 69 forming projections extending inwardly from the surface of the cylindrical portion 62. When the vanity case is to be filled with powder the dispensing member 59 is removed, and as much powder as desired may be introduced into the compartment 64, whereupon the dispensing member 59 is replaced in position. Thereafter by reason of a normal

amount of handling to which a vanity case is subjected and its contact with other objects in a pocketbook, a certain amount of powder seeps through the porous material 68 and lodges upon the under side of the puff 66. Thus the puff is at all times ready for use, and if an additional amount of powder is desired it can be readily scraped from the upper side of the material 68, and additional powder can be forced through the material 68 by pressing upwardly the bottom of the pouch 20. In fact any amount of powder can readily be forced through by manipulation of these two flexible members and by forcing them against the resilient puff 66.

15 Referring to Figures 1 and 2, it may be desired to enclose the pouch 20 in a protective or ornamental covering. To that end there is secured between the lower portion 23 of the ring 21 and the annular part 20b of the material 20 a rim 71 of a ring 72 which also has a depending portion 73. Extending circumferentially around the depending portion 73 are a plurality of evenly spaced holes for the attachment to the ring 72 of links 74 constituting the upper links of a mesh bag 25 75 which may be of metal or other suitable material. In assembling the portion 20b, the bezel member 61 and the ring 72, with the ring 21, the rim 60, the portion 20b and the rim 71 are located between the portions 22 and 23 in the manner shown, and these portions are then firmly compressed together with a tool forcing the rims 60 and 71 against the material 20b and securely holding these parts together by the elasticity of the metal. A slight indentation is preferably caused in one or both of the rims, for example in the rim 60 by this operation, thus securely holding the leather 20b to the metal parts.

Referring now specifically to Figure 2, instead of the dispensing member 59, I may provide a dispensing member 59a having a rolled-over or beaded annular portion 67a and a porous bottom 68a. Preferably the bottom part 68a is made of metal screening. The dispensing member 59a, which is dish-shaped as shown, has a somewhat more permanent shape than the dispensing member 59.

Referring now to Figures 3 and 4, there is therein shown a dispensing device 77 having integrally formed therewith a rim 78 which may be like the rim 60 and connected to the ring 21 in the same manner. This dispensing device 77 is dish-shaped being shown as having cylindrical sides and a flat bottom. Comparing Figures 3 and 4 it will be noted that there is a circular opening 79 eccentrically located in the bottom of the device 77. Pivotally fastened to this bottom by a rivet 80 at the center thereof is a disc 81 having a handle 82 by means of which it may be turned. Referring now to Figure 3, there is a cluster of holes 83 in the bottom of the member 77, and another cluster of holes 84 in the disc 81. The disc 81 likewise has a large circular opening 85 of the same size as the opening 79 and so located in the disc that when the latter is turned to a particular angular position the holes are concentric. With the disc brought to that position the compact may be readily filled. At all other positions of the disc 81 one of the openings 79 or 85 is in alignment with some of the individual holes of the clusters 83 or 84, and consequently the device in that position acts as a sieve to allow a certain amount of powder to come through onto the puff 66. It is noted that powder can be caused to spurt through these holes by using the bag or pouch 20 as a bellows.

Referring now to Figures 5 and 6, there is therein illustrated a vanity case having a dispensing and powder puff holding member 87. The member 87 is dish-shaped and preferably has a cylindrical wall and a rim 88 which may be like the rim 78 and the rim 60 and attached to the ring 21 and the material 20 in the manner already described. At or near the central portion of the bottom of the dish-shaped member 87 is an annular ridge 89 surrounding and bounding a central opening 90 which is conveniently made circular, although so far as certain features of the invention are concerned it might be of a different shape. The powder puff 66 located in the compartment 91 formed by the member 87 normally seals the opening 90. The annular ridge 89 forms for itself a seat in the pile of the puff, thus making an effectual seal to the compartment 92 below the member 87 where the powder is located and into which it may be readily introduced through the opening 90 by simply removing the puff. The same bellows action already described may be used for introducing a quantity of powder onto the puff 66, and in fact mere carrying of the vanity case insures the deposit of sufficient powder onto the puff through the opening 90. In order that the seal already described may be at all times maintained when the cover 28 of the vanity case is closed, as shown in Figure 5, the dimensions of the parts are desirably such that the puff will be to a certain extent compressed.

As shown in Figure 5, a mirror 93 is substituted for the rouge holding member 36, and it interfits with the retaining ring 41 in the manner already described. This mirror 93 being irremovably fixed in position and having no part swinging with relation to the cover piece renders the sealing of the vanity case of Figures 5 and 6 easily and quickly accomplished and the mirror serves to compress the puff into the position shown in Figure 5.

Referring now to Figure 6, desirably the ridge 89 is threaded as shown at 94, and a cap 95 with sifter openings 96 may be screwed in position if desired. By the use of the sifter cap 95 the amount of powder delivered to the puff 66 is reduced. In connection with certain uses of the vanity case this may be desired.

It is noted that the chain mesh enclosure 75 is shown in Figures 1 and 2 but not in Figures 4, 5 and 6. It should be understood that this ornamental and protective pouch may be used in connection with any of the modifications of the invention or omitted in any case. Certain specific advantages of using this mesh enclosure have been pointed out and nevertheless where a lighter or more inexpensive device is desired, or where the leather finish is particularly wanted, the outer covering may be omitted.

It will thus be seen that there has been provided by this invention an article in which the various objects hereinabove set forth, together with many thoroughly practical advantages, are successfully achieved.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In an article of the class described, in combination, a ring substantially U-shaped in cross-section with the free ends facing inwardly, an

annular member of thin but relatively stiff material secured in place between the said free ends of the ring, a flexible pouch of impervious material also secured between the free ends of the 5 ring and below the said annular member, and a piece of pervious material constituting a sifter in said pouch and normally retained therein by said annular member.

2. In an article of the class described, in combination, a ring substantially U-shaped in cross-section with the free ends facing inwardly, an annular member of thin but relatively stiff material secured in place between the said free ends of the ring, a flexible pouch of impervious material also secured between the free ends of the 10 ring and below the said annular member, a piece of pervious material constituting a sifter in said pouch and normally retained therein by said annular member, and a cover hinged to said 15 ring at the outside thereof.

3. In an article of the class described, in combination, a ring substantially U-shaped in cross-section having the spaced free ends thereof facing inwardly, a flexible impervious pouch having its edge portion disposed within said ring between said ends, and means including a perforated part covering substantially the mouth portion of said pouch and spaced from the bottom thereof, said means including an edge portion 25 disposed between said ends of said ring, said ends being clamped against said edge portions of said 30 means and said edge portion of said pouch to hold said pouch and said means in position.

4. In an article of the class described, in combination, a ring substantially U-shaped in cross-section having the spaced free ends thereof facing inwardly, a flexible impervious pouch having its edge portion disposed within said ring between said ends, means including a perforated part 35 covering substantially the mouth portion of said pouch and spaced from the bottom thereof, said means including an edge portion disposed between said ends of said ring, said ends being clamped against said edge portion of said means 40 and said edge portion of said pouch to hold said pouch and said means in position, and a cover hingedly secured to said ring.

5. In an article of the class described, in combination, a ring substantially U-shaped in cross-section having the spaced free ends thereof facing inwardly, a flexible impervious pouch having its edge portion disposed within said ring between said ends, an annular flange member disposed between the ends of said ring and extending inwardly therefrom, said ends being clamped on said flange member and said edge of said pouch to hold said pouch and said flange member in position, and a perforated part secured to and supported by the inwardly extending portion of said flange member to cover the mouth portion of said pouch.

6. In an article of the class described, in combination, a ring substantially U-shaped in cross-section having the spaced free ends thereof facing inwardly, a flexible impervious pouch having its edge portion disposed within said ring between said ends, an annular flange member comprising a horizontal portion fitting between said ends of said ring, a vertical portion extending 65 downwardly therefrom, and an inwardly extending portion spaced below said horizontal portion, said vertical portion having an annular ridge formed therein spaced above said inwardly extending portion, a ring part adapted to snap over 70 said ridge portion and rest upon said inwardly 75

extending portion, and a piece of pervious material secured to said ring part to separate the lower portion of said pouch from the upper portion thereof.

7. In an article of the class described, in combination, a ring member generally U-shaped in cross-section and having its free spaced ends extending inwardly, a flexible impermeable pouch having its edge portion disposed between said ends, and a flange member having a horizontal portion disposed between said ends and a substantially vertical portion extending downwardly therefrom, an annular part having a horizontal portion disposed between said ends and a vertical portion extending downwardly adjacent the side of said pouch opposite the vertical portion of said flange member, said ends being clamped together to hold said horizontal portions of said flange member, said annular part and said edge portion of said pouch so that the portion of said pouch adjacent said ring member is clamped between said vertical portions of said flange member and said annular part, and means forming a powder sifter shaped to interfit with the vertical portion of said flange member to separate the upper and lower portions of said pouch.

8. In an article of the class described, in combination, a ring member generally U-shaped in cross-section and having its free spaced ends extending inwardly, a flexible impermeable pouch having its edge portion disposed between said ends, a flange member having a horizontal portion disposed between said ends and a substantially vertical portion extending downwardly therefrom, an annular part having a horizontal portion disposed between said ends and a vertical portion extending downwardly adjacent the side of said pouch opposite the vertical portion of said flange member, said ends being clamped together to hold said horizontal portions of said flange member, said annular part and said edge portion of said pouch so that the portion of said pouch adjacent said ring member is clamped between said vertical portions of said flange member and said annular part, and means forming a powder sifter shaped to interfit with the vertical portion of said flange member to separate the upper and lower portions of said pouch, and a cover hingedly connected to said ring member.

9. In an article of the class described, in combination, a ring substantially U-shaped in cross-section having the spaced free ends thereof facing inwardly, a flexible impervious pouch having its edge portion disposed within said ring between said ends, and a cup-shaped member having substantially horizontal flange portions extending between said ends, said ends being clamped down upon said flange portions and said edge portion of said pouch, said cup member extending into said pouch to separate the lower and upper portions thereof and having perforations formed in the bottom surface thereof.

10. In an article of the class described, in combination, a ring substantially U-shaped in cross-section having the spaced free ends thereof facing inwardly, a flexible impervious pouch having its edge portion disposed within said ring between said ends, a cup-shaped member having substantially horizontal flange portions extending between said ends, said ends being clamped down upon said flange portions and said edge portion of said pouch, said cup member extending into said pouch to separate the lower and upper portions thereof and having

perforations formed in the bottom surface thereof, and a disk rotatably mounted on the bottom of said cup member, said disk having perforations formed therein positioned to register with the perforations in the bottom of said cup member when said disk is in certain positions.

11. In an article of the class described, in combination, a ring substantially U-shaped in cross-section having the spaced free ends thereof facing inwardly, a flexible impervious pouch having its edge portion disposed within said ring between said ends, a cup-shaped member having substantially horizontal flange portions extending between said ends, said ends being clamped down upon said flange portions and said edge portion of said pouch, said cup member extending into said pouch to separate the lower and upper portions thereof and having perforations formed in the bottom surface thereof, and a cover hingedly secured to said ring.

12. In an article of the class described, in combination, a ring substantially U-shaped in cross-section having the spaced free ends thereof facing inwardly, a flexible impervious pouch having its edge portion disposed within said ring between said ends, a cup-shaped member having substantially horizontal flange portions extending between said ends, said ends being clamped down upon said flange portions and said edge portion of said pouch, said cup member extending into said pouch to separate the lower and upper portions thereof and having perforations formed in the bottom surface thereof, and a member secured to the bottom of said cup member and having perforations formed therein, said member being movable into and out of a position in which the perforations in the bottom of said cup member and the perforations in said member are in registry.

13. In an article of the class described, in com-

bination, a ring substantially U-shaped in cross-section having the spaced free ends thereof facing inwardly, a flexible impervious pouch having its edge portion disposed within said ring between said ends, a cup-shaped member having substantially horizontal flange portions extending between said ends, said ends being clamped down upon said flange portions and said edge portion of said pouch, said cup member extending into said pouch to separate the lower and upper portions thereof, the bottom of said cup member having a threaded hole formed therein, and a perforated cap member threaded over said hole.

14. In an article of the class described, in combination, a ring substantially U-shaped in cross-section having the spaced free ends thereof facing inwardly, a flexible impervious pouch having its edge portion disposed within said ring between said ends, a cup-shaped member having substantially horizontal flange portions extending between said ends, said ends being clamped down upon said flange portions and said edge portion of said pouch, said cup member extending into said pouch to separate the lower and upper portions thereof, the bottom of said cup member having a hole formed therein bordered by an upturned threaded flange, and a perforated cap member threaded over said flange.

15. In an article of the class described, in combination, a ring member, a flexible impermeable pouch connected to said ring member, a flange member connected to said ring member within said pouch and having an inwardly extending horizontal portion, said flange member having a ridge formed therein spaced above the horizontal portion thereof, and a powder sifter including a ring adapted to snap under said ridge and rest on said horizontal portion.

ALFRED F. REILLY.
